UNITED STATES PATENT OFFICE.

ARTHUR D. NICHOLSON AND WILLIAM T. LOWERY, OF FREDERICKSBURG, VIRGINIA.

DISPENSING APPARATUS.

1,260,433.

Specification of Letters Patent. Patented Mar. 26, 1918.

Application filed November 25, 1916. Serial No. 133,457.

To all whom it may concern:

Be it known that we, ARTHUR D. NICHOLSON and WILLIAM T. LOWERY, both citizens of the United States of America, residing at 5 Fredericksburg, in the county of Spotsylvania and State of Virginia, have invented certain new and useful Improvements in Dispensing Apparatus, of which the following is a specification.

10 This invention relates to a dispensing apparatus and it has for its object the provision of a pleasing and ornamental structure adapted to be located at the curb line and to dispense gasoline or other fuel oils 15 or lubricating oils to motorists.

One of the principal objects of the invention is to so construct the device that the oil being delivered to the motorist will first be delivered into a transparent receptacle so 20 that the motorist may feel sure that he is receiving the full amount of oil that he pays for, the oil being first delivered into the transparent receptacle in full view of the motorist and delivered from said transparent receptacle into the tank of the automobile through a pipe having no other connection with the dispensing apparatus than 25 through the transparent receptacle.

A further object of the invention is the 30 provision of improved means to prevent unauthorized persons from drawing oil from the dispensing apparatus and a still further object of the invention is to provide means to prevent fraudulent operation of the dispensing apparatus upon the part of dishonest employees.

Further objects and advantages of the invention will be set forth in the detailed description which now follows:

40 In the accompanying drawings;

Figure 1 is a view partly in side elevation and partly in section of a dispensing apparatus constructed in accordance with the invention.

45 Fig. 2 is a view like Fig. 1 but upon an enlarged scale and with parts broken away.

Fig. 3 is a detail view of the key herein-after described.

Fig. 4 is a detail view of a hinged locking 50 plate herein-after described, and

Fig. 5 is a detail view of a notched disk herein-after described.

Like numerals designate corresponding parts in all of the figures of the drawing.

In carrying out the invention we provide 5 an underground storage tank 5 having the usual filling cap 6. An air supply pipe 7 for supplying compressed air to the tank 5 leads into the upper portion of said tank and this pipe 7 is preferably provided with a 10 gage 8 so that the degree of pressure within the tank 5 may be readily ascertained. The supply pipe 9 for the dispensing apparatus leads from a point adjacent the bottom of the tank 5 and extends upwardly through an 15 ornamental pedestal 10. A plate 11 is seated upon the upper end of this pedestal and is provided with a groove 12 in its upper face, said groove receiving the lower end of a glass cylinder 13. The lower edge of the 20 cylinder rests upon packing 14 disposed within the groove 12. Any suitable kind of packing may be employed though I find lamp-wick soaked in shellac to be advantageous for this purpose because it resists 25 the action of the gasoline.

The upper edge of the glass cylinder 13 is disposed in a groove 15 formed in the under face of a plate 16 and the plates 11 and 16 are drawn together by tie-rods and nuts 17 30 and 18 to thereby provide a fluid tight receptacle. The upper end of the supply pipe 9 is threaded into the plate 11 and carries a T 19 that is disposed within the cylinder 13 and through the branches of which T the 35 gasoline is discharged into the cylinder 13. The supply pipe 9 is provided with a controlling valve 20. A discharge pipe 21 which leads from the underside of the plate 11 is provided with a controlling cock 22. 40 A flexible hose, a portion of which is indicated at 23, serves to convey the gasoline or other oil to the tank of an automobile. The transparent receptacle formed by the cylinder 13 and the plates 11 and 16 constitutes 45 a measuring chamber of predetermined capacity and, if desired, this chamber may be graduated in gallons or otherwise as indicated by the lines 24. To permit the escape 50 of any air trapped within the receptacle, a check valve 25 of such buoyancy as to be lifted by the gasoline is arranged to close a vent 26 when the receptacle is full. The check valve is prevented from falling out of

2
a cavity 27 in which it is located by means of a perforated plate 28 carried by the plate 16. It is apparent that with the valve 22 closed and the valve 20 opened, gasoline 5 under pressure will flow through the supply pipe 9 into the receptacle and fill the same. After this receptacle or measuring chamber has been filled to the desired point, the valve 20 will be closed and the valve 22 will be 10 opened whereupon the gasoline or other oil within the measuring chamber may flow through the discharge pipe 21 and hose 23 to the tank of a waiting vehicle.

It is apparent, however, that since the apparatus herein shown and described is located at the curb line means must be provided to prevent unauthorized persons from operating the same to extract oil therefrom since otherwise dishonest persons could 20 empty the tank 5 after nightfall when the garages at which these devices are usually employed are closed. To render it impossible for unauthorized persons to operate the apparatus, the valve 20 is constructed to be 25 spring actuated. That is, it is moved to closed position by a spring 29 which encircles its stem 30. It is, therefore, apparent that a pull must be imparted to this stem against the tension of the spring in order to 30 open the valve. To accomplish this the key shown in Fig. 3 is used. This key comprises a shank 31 of tubular formation which is adapted to fit over the ends of the valve stem 30 and is provided with a bayonet slot 32 adapted to engage a pin 33 carried by the valve stem. By engaging the tubular shank 31 with the valve stem and grasping the handle 34 of the key, the operator may pull the valve stem outwardly and thereby 40 quickly open the valve. To render it unnecessary for the operator to hold the valve in its open position the shank 31 is provided with a lateral extension 35 which passes outwardly through a slot 36 formed in the wall 45 of the pedestal 10, when the valve is being opened and by imparting a turning movement to the shank 31 to cause the lateral extension 35 to engage the outer face of the wall of the pedestal the valve will be held in 50 its open position against the tension of the spring 29. A hinge plate 37 secured to the wall of the pedestal 10 constitutes a shutter which is adapted to close the opening 36 and to be secured in its closed position by a padlock 38 after the key 31 has been removed. It will, therefore, be apparent that for an 55 unauthorized person to tamper with this apparatus it would not only be necessary for such person to have a key of the peculiar form herein shown but he would also have to possess a key to the padlock. Thefts of automobiles by "joyriders" are common and persons of this type would not hesitate to 60 break a padlock if they found it necessary

to do so in order to secure gasoline but even 65 if they break the padlock herein shown and described they still will not be able to actuate the peculiar type of valve herein employed because this valve is not operated by a turning action like most valves but must 70 be actuated by a longitudinal pull and this pull must be imparted to it through a comparatively narrow orifice.

It is not only necessary to guard against 75 the direct theft of the gasoline but it is also necessary to guard against loss through dishonest employees. It is apparent that unless means are provided to prevent it, gasoline could be allowed to flow directly from tank 5 to hose 23 by opening valves 20 and 22 simultaneously and to prevent this means are provided for preventing the actuation of valve 20 until the valve 22 has been entirely closed and to prevent the opening of the valve 22 except when the valve 20 is closed. 85 To this end the valve stem 30 is continued beyond the valve casing and is pivoted at 38 to the lower end of a lever 39. This lever is pivoted at 40 to a lug carried by the pedestal 10. The upper end of the lever 39 carries a 90 pin 41 which projects through the wall of the pedestal and coacts with a disk 42 that is carried by the turning plug of valve 22, it being understood that this valve is of the plug type. The disk 42 is provided with a 95 notch 43 which lies in alignment with the pin 41 and within which said pin enters when the valve 22 is in its closed position. When the valve stem 29 moves to the right in Fig. 1 it rocks the lever 39 upon its pivot 40 and 100 withdraws the pin 41 from the notch 43 whereupon the valve 22 may be opened but as long as the valve 22 is open the flat rear face of the disk 42 prevents the movement of the pin 41 toward the right consequently, 105 during all of the time that the valve 22 is open, valve 20 will be closed and it is only when valve 22 is closed and the notch 43 is brought in alignment with pin 41 that the valve 20 may be opened by moving the stem 110 30 toward the left in Fig. 1. It will thus be seen that by a very simple and inexpensive mechanism means are provided to prevent loss to the garage owners through improper manipulation of the apparatus by dishonest 115 employees.

Nearly all garages have compressed air tanks for the purpose of inflating tires. The pressure in these tanks ranges from ninety to one hundred and twenty-five pounds. It 120 is not desirable to have more than ten pounds pressure in the supply tank 5 yet it is desirable to be able to supply tank 5 from the usual compressed air tank that provides the pressure for inflating tires. To avoid 125 the necessity of constantly watching the gage 8 and frequently replenishing the pressure in tank 5 as the gasoline is withdrawn

therefrom, we provide a reducing valve 44 in the pipe 7 it being understood that this pipe is connected to the tire inflating air tank (not shown). This reducing valve will 5 serve to automatically maintain any desired pressure in the tank 5 irrespective of how the pressure may fluctuate in the tire inflating tank.

It is to be understood that the invention 10 is not limited to the precise construction set forth but that it includes within its purview whatever changes fairly come within the spirit of the appended claims.

Having described our invention what we 15 claim is:—

1. In a device of the character described, the combination with a pedestal of a transparent measuring receptacle located thereon, a storage tank located beneath the surface 20 of the ground, a supply pipe leading from said storage tank to said receptacle through said pedestal, means for supplying compressed air to the storage tank, a discharge pipe leading from said receptacle, a controlling valve inclosed by said pedestal in 25 said supply pipe, a spring for actuating said valve and a removable key for actuating said valve against the tension of said spring, said valve being inaccessible except by 30 means of said key.

2. A dispensing apparatus of the character described, comprising a pedestal, a transparent measuring receptacle located thereupon, a supply pipe leading to said receptacle and inclosed by said pedestal, a spring actuated valve in said discharge pipe and located within the pedestal, said valve comprising a longitudinally movable stem and a spring for actuating the same to close the 35 valve, a removable key adapted to engage said valve stem to impart longitudinal movement thereto, said valve being inaccessible except by means of the key, said pedestal being provided with an opening through 40 which said key may be inserted.

3. A dispensing apparatus of the character described, comprising a pedestal, a transparent measuring receptacle located thereupon, a supply pipe leading to said receptacle through said pedestal, a spring actuated valve in said discharge pipe and inclosed by said pedestal, said valve comprising a longitudinally movable stem and a spring for actuating the same to close the 45 valve, a removable key adapted to engage said valve stem to impart longitudinal movement thereto, said pedestal being provided with an opening through which said key may be inserted and a lateral extension 50 carried by said key adapted to engage a part of the pedestal to hold the valve in opened position and against the tension of the spring.

4. A device of the character described,

comprising a pedestal, a transparent measuring receptacle mounted thereupon, a supply pipe leading from a source of supply to the measuring receptacle and inclosed by said pedestal, a spring actuated valve located in said supply pipe and comprising a longitudinally movable stem, a discharge pipe leading from the receptacle, a valve located in said discharge pipe and comprising a rotative element having a notch formed therein, a pivoted lever connected to the pedestal, 70 one end of said lever being pivoted to the valve stem and the other end of said lever carrying a pin coöperating with said notched rotative element, said pin being held out of engagement with said member when the 80 spring actuated valve is closed and engaging in the notch of said member to prevent movement of the valve in the discharge pipe as long as the valve in the supply pipe is open.

5. A device of the character described comprising a pedestal and a transparent measuring receptacle mounted thereupon, a supply pipe leading to said receptacle and inclosed by the pedestal, said pedestal having an opening formed in the wall thereof, 90 a spring actuated valve in said supply pipe comprising a longitudinally movable valve stem and a key adapted to be inserted through the opening in the pedestal, said 95 key having a bayonet slot formed therein and being adapted to fit over said valve stem and said valve stem having a member adapted to engage in said bayonet slot.

6. A device of the character described, comprising a compressed air storage tank 100 for gasolene, a pedestal, a transparent measuring receptacle upon said pedestal, a supply pipe leading from said tank to said receptacle, a spring actuated valve in the supply pipe, said valve having a longitudinally movable valve stem, a lever pivoted intermediate its ends to the pedestal and pivoted at one end to said valve stem, a discharge pipe leading from the receptacle and located 110 entirely outside of the pedestal, a controlling cock in the discharge pipe, a disk secured to the turning member of said cock and having its rear face disposed adjacent the outer face of the pedestal, said disk having a notch formed therein and a member carried by the other end of said lever and adapted to cooperate with said disk as and for the purposes set forth.

7. A device of the character described 120 comprising a measuring receptacle, a hollow pedestal upon which said receptacle is mounted, a supply pipe leading to said receptacle through the pedestal, a spring actuated valve in the supply pipe, said valve 125 having a longitudinally movable valve stem which projects in both directions from the valve casing, said pedestal having an open-

ing in alinement with one end of the valve stem, a key adapted to be passed through said opening and to engage the valve stem to impart an endwise pull thereto, a lever pivoted at its lower end to the opposite end of the valve stem and pivoted intermediate its ends to the pedestal, a discharge pipe leading from the receptacle and located entirely outside of the pedestal, a controlling 10 cock in the discharge pipe, a disk secured to the controlling member of said cock and having its face disposed adjacent the outer face of the pedestal, said disk having a notch formed therein and a member carried 15 by the other end of said lever and adapted

to coöperate with said disk as and for the purposes set forth.

In testimony whereof we affix our signatures in presence of two witnesses.
